UNITED STATES PATENT OFFICE.

FREDRICK HABICH, OF GRAND FORKS, NORTH DAKOTA.

WATER-JACKETED FLUE.

SPECIFICATION forming part of Letters Patent No. 587,809, dated August 3, 1897.

Application filed October 20, 1896. Serial No. 609,411. (No model.)

To all whom it may concern:

Be it known that I, FREDRICK HABICH, a citizen of the United States, residing at Grand Forks, in the county of Grand Forks and State 5 of North Dakota, have invented certain new and useful Improvements in Water-Jacketed Flues; and I do hereby declare the following to be a full, clear, and exact description of the invention, such as will enable others skilled 10 in the art to which it appertains to make and use the same.

My invention has for its object to provide an improvement in the nature of a water-jacketed flue.

15 As is well known, the water contained in the water-tanks of railway water-stations is in cold weather kept sufficiently warm to prevent the same from freezing by the heat from a draft-flue which is run through the tank. 20 These tanks are usually constructed of wood. The draft-flue in some cases extends from a stove and in other cases from the fire-pot of a boiler, either of which is usually located in the closed apartment below the water-tank.

25 My invention while capable of a more extended use has for its especial object to provide a suitable water-jacket for preventing the flues from igniting or setting fire to the floor or bottom of these railway-tanks through 30 which they are passed.

To these ends my invention consists of the novel devices and combinations of devices hereinafter described, and defined in the claims.

35 The preferred form of my invention (shown in working position between the flue and the tank-bottom of one of these railway water-stations) is illustrated in the accompanying drawings, wherein, like letters referring to 40 like parts throughout the several views—

Figure 1 is a view, partly in side elevation, with some parts broken away, and partly in central vertical section, showing an ordinary railway water-station with my invention applied thereto. Fig. 2 is an enlarged view, partly in perspective and partly in central vertical section, showing my improved water-jacket and the immediate flue connections thereto. Fig. 3 is a plan view of the parts 45 shown in Fig. 3; and Fig. 4 is a detail view in plan, showing the clamping-ring used in connection with my improved water-jacket.

Referring to the parts of the water-station,

1 indicates the water-tank provided with a plank and timber bottom 2 and supported by 55 the walls and timbers of an under apartment 3.

4 indicates the boiler of an engine or pump located in the apartment 3 and provided with a draft-flue 5 6, which extends upward through the floor or bottom 2 of the tank 1 and also 60 through the top of the same.

7 indicates the pivoted water-delivery spout used in filling the engine-tanks from the water-tank 1, and 8 indicates the railway-track which passes the said station. 65

All of the above-mentioned parts with the exception of the draft-flue 5 6 are of the ordinary construction and require no further comments for the purpose of this case. It will be noted, however, that the tank 1 is partially filled with water, as indicated at 2.

Referring now to the application of my improved water-jacket, attention is first called to the fact that the flue-sections 5 and 6 are united some little distance below the bottom 70 2 of the tank 1 by the engagement of screw-threads 5^a 6^a cut, respectively, on the said flue-sections 5 and 6. 75

In the construction shown the water-jacket is in the form of a cast cylinder A of considerably larger diameter than the flue-section 6. At its upper end this jacket or cylinder A is provided with an outturned flange B, provided with bolt-holes C, and at its lower end is contracted and provided with internal screw-threads D. In order to place this jacket A in working position, the plank portion of the tank-bottom 2 is cut out to snugly fit and pass said cylinder A, and when said cylinder or jacket A is placed in working position its 90 screw-threaded portion D is screwed onto the screw-threads 6^a of the flue-section 6, thereby forming a water-tight joint therewith, and the flange B will rest upon the upper surface of said tank-bottom 2. In thus securing the 95 parts together it will be understood, of course, that the screw-threaded portion D of the jacket A must be screwed onto the screw-threads 6^a of the flue-sections 6 before the said screw-threads 6^a are screwed into the 100 screw-threads 5^a of the flue-section 5.

E indicates a clamping-ring provided with bolt-holes F. This clamping-ring E is adapted to fit over the cylindrical jacket A and to be clamped against the under side of the 105 plank portion of the tank-bottom 2 by means

of nutted bolts G, which are passed through the perforations F and perforations C of the clamping-ring E and flange B, respectively, and also through said plank bottom. In 5 practice some suitable packing material (not shown) will usually be clamped between the flange B and the planks of the tank-bottom. 2. With this construction, as is obvious, all portions of the tank-bottom 2 are protected 10 by the water-jacket from the flue, and hence all danger of the same being ignited or set on fire by the heat from the same is effectually prevented. Again, the water contact with the flue is greatly increased by the wa- 15 ter-jacket. The water which is constantly being heated in the annular chamber formed between the flue and the water-jacket will, under the action of convection, continually rise to the top of the tank, while the cooler 20 portions of the water will lower to keep said water-jacket filled.

As already indicated, my improved water-jacket is capable of more general use than that just specifically described. For example, the same might be used as a water-jacket to a stove-pipe which is run through the ceiling of one room into another or through the roof of a building. In either of these cases the water-jacket should of course be kept 25 filled with water. When the water-jacket is placed in the floor of a room, it would serve another very desirable function, to wit: It will cause the evaporation of a small amount of water into the room, sufficient to keep the 30 air properly moistened. It will also be understood that various alterations in the details of construction above set forth may be made without departing from the spirit of my invention. 35 40 What I claim, and desire to secure by Letters Patent of the United States, is as follows:

1. The combination with a flue and the floor or other part through which the same passes, of a water-jacket open at its upper end and supported from the floor, and connecting with the flue by a water-tight joint, at a point below the floor, substantially as described. 45

2. The combination with a water-tank and a flue passing upward through the same, of 50 a water-jacket surrounding said flue where it passes through the bottom of said tank open at its upper end to the interior of said tank and depending therefrom to increase the water-heating surface of said flue and to 55 protect said tank-bottom, substantially as described.

3. The combination with a water-tank and a flue passing upward through the bottom of the same, of a water-jacket surrounding the 60 flue where it passes through the tank-bottom, which jacket is open to the tank at its upper end and forms a tight joint with the flue at its lower end, below the floor, substantially as described. 65

4. The combination with the water-tank, of the smoke-flue passing through the same and the water-jacket surrounding the said flue where it passes through the floor of said tank, which jacket is open to the tank at its upper end and is provided at its lower end with the contracted and internal-threaded portion, adapted to form a tight joint with the flue, below the floor, substantially as described. 70 75

In testimony whereof I affix my signature in presence of two witnesses.

FREDRICK HABICH.
